United States Patent Office

Des. 186,000
Patented Aug. 25, 1959

186,000

STEERING WHEEL

Glenn W. Monigle, Pittsburgh, Pa., assignor to Attwood Brass Works, Inc., Grand Rapids, Mich., a corporation of Michigan

Application May 14, 1958, Serial No. 50,889

Term of patent 14 years

(Cl. D71—1)

Fig. 1 is a perspective view of my new design for a steering wheel.

Fig. 2 is a front elevation view thereof.

Fig. 3 is a side elevation view thereof.

Fig. 4 is a bottom view thereof.

Fig. 5 is a sectional view taken along the plane V—V of Fig. 2.

Fig. 6 is a sectional view taken along the plane VI—VI of Fig. 2.

The essential features of my design reside in the portions shown in solid lines.

I claim:

The ornamental design for a steering wheel, substantially as shown and described.
